Ill., assignors to Goss Printing Press Company,
a corporation of Illinois**

Application November 23, 1927, Serial No. 235,381

22 Claims. (Cl. 270—9)

The invention relates to novel and useful improvements in perfecting printing presses and more especially to such novel and useful improvements for producing a great variety of different sized products varying optionally and successively by the smallest successive page increments up to the full capacity of the press.

10 Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a diagrammatic elevation of a printing press, showing certain features of the invention;

25 Fig. 2 is a top plan corresponding to Fig. 1;
Fig. 3 is an enlarged elevation, in greater detail.

Fig. 3 is an enlarged elevation, in greater detail, of one section or part of the printing press, and comprises substantially one quarter of Fig. 1;

Fig. 4 is a further enlarged detail, with parts 30 in section and parts broken away, of the two-speed driving mechanism:

speed driving mechanism;

Fig. 5 is a detached detail of the split collar for the driving bevel gear, and is taken on the line 5—5 of Fig. 4;

35 Fig. 6 is a central, vertical, transverse section taken substantially on the line 6—6 of Fig. 4;

Fig. 7 is a diagrammatic plan of one arrangement of the slow speed sheet cutting mechanism and one of the four main and

40 Fig. 8 is a similar view of another arrangement of the half-speed, half-width sheet cutting mechanism and one of the formers.

The invention is directed principally to producing from a press of given maximum capacity, any desired size of product from the smallest to the largest product by optional increments of only two pages, thus giving a complete range of selection as to the size of the product, between the greatest and least capacity of the press by the successive

50 and least capacity of the press by the successive least possible increments. The invention in the present preferred embodiment is applied to a press of the unit type, and preferably to such a press having two series of perfecting units arranged in two lines or series, one superimposed upon the other, although in certain of its aspects

the invention is also applicable to other types and kinds of presses.

With this main object in view, and other objects as well, a press is provided wherein a plurality of perfecting units, one or more of the printing units being adapted to run at either full or half-speed, may be arranged selectively to supply perfected webs of various selected widths to a folding mechanism. When one or more of the perfecting units is run at half-speed, a mechanism is provided for cutting the perfected half-speed web, of a selected fractional width, into sheets and feeding these sheets in intermittent or spaced-apart relation with respect to the pages upon the full speed perfected webs, all being directed in the desired association into the folder. The slow-speed perfecting mechanism operates optionally upon a full width, three-quarter width, half-width or quarter-width web, and these webs may be directed into various associated relations with the full-speed perfecting webs, the slow-speed perfected web being usually preliminarily severed into sheets. Thus successive increments of only two pages, the smallest possible increment unit, may be supplied to secure any product between the smallest and largest possible capacity of the press.

As previously indicated, the invention is preferably embodied in the unit type of press, the perfecting printing units being arranged in line series, and preferably in two superimposed series, and the folding mechanisms, consisting of four formers and two cross-folders, are preferably interposed between each successive group of four perfecting units. 35

Either all of the perfecting printing units, or alternate or other selected units in a given row, may be driven at either full or half-speed at will. Usually the groups of units furnishing webs for common association will require only one slow-speed unit to supply all necessary sizes of products. The feed rollers from the various units are, of course, likewise arranged to run either at full or half-speed to correspond with their respective press units. Half-width, reversible angle bars are provided for each printing unit, there being a slitting mechanism between each unit and its angle bar, and the slitting unit will of course be adapted to run at either full or half-speed. 40 45

A half-speed sheet-cutting mechanism is provided for each of the variable-speed perfecting units, and is located between the angle bars for that unit and the corresponding former. In so far as concerns the broader aspects of the invention, this sheet-cutter will be of half-width 55

and may be stationary with respect to its particular former. Thus the perfected sheets from the half-speed printing unit would be associated with every other successive page along one or more perfected webs coming from one or more of the full-speed perfecting units. If the variable-speed perfecting unit is run at full speed, the sheet cutter will of course be silenced. It will be obvious that two or more of the half-speed sheet-cutters can be employed in various locations and relations as may be found useful or desirable.

The web supply for the variable speed unit or units may be the usual web supply, and web rolls of various widths may be used. A quarter-width web could be run to give an increment of two pages over the full capacity of the full-speed units running to the same former, and a half-width web could be run to give a like increment of four sheets. A three-quarter width web could be run, employing the slitter, and the slit quarter web would be run over the angle bar and associated with the half-web prior to cutting, in case only one half-speed sheet cutting mechanism is employed. Thus for every product it would be possible to optionally run two, four or six pages from the half-speed unit as desired increments to the full capacity of webs coming from any number of full-speed perfecting units running from the same former.

30 As a further feature, increasing the flexibility of this press, a half-width web supply roll may be run centrally through the printing unit, this half-width web being centrally slit, and either half thereof run to one of the side-by-side formers. Thus two-page increments could be run to either cross-folder from a single half-width web supply roll. In connection with this run of web, it is provided that the half-speed sheet-cutter may be variably positionable across the press, and thus be brought into alignment with this particular run of web; that is, the sheet-cutter could be moved along its shaft so that it is half-way in line with either former.

45 In the present preferred and exemplarily dis-
closed embodiment of the press, which is of the
unit type, two perfecting units are arranged in
line series, with two similar units in superposition
thereabove; next in line is a folding mechanism
having side-by-side formers in line with the low-
50 er printing units and like side-by-side formers in
line with the upper printing units, these latter
being generally used to a relatively much less ex-
tent. The folding mechanism includes also two
55 cross-folders in the usual relation to the verti-
cally-disposed formers. Preferably there are sev-
eral such groups or arrangements of printing
units and folders in longitudinal series in a single
press, depending upon the maximum size product
which is desired.

60 The paper supply for the perfecting units of the lower series is located preferably below, and the paper supply for the upper series of perfecting units is located preferably above the respective series of printing units, the perfected webs running from the two series of units into the intervening space, and therethrough and therefrom are directed to the folding mechanism. In this intervening space are located the web guiding rollers, the slitters, reversible half-width angle bars, and one or more of the half-width, half-speed sheet-cutters, the product from all of these being directed selectively to the heads of the desired formers, and so in association into the folders.

65

70

75 Referring now to the embodiment of the in-

vention, illustrated by way of example in the accompanying drawings, there is shown diagrammatically in Figs. 1 and 2 a preferable arrangement of printing units and folding mechanisms, and a size of press well adapted for the universal requirements of many if not most metropolitan dailies, but the particular mechanisms by which we attain the great diversity in the full range of sizes of products from the least to the greatest capacity of the press, with all intervening sizes in increments of only two pages, are best shown in the subsequent figures.

In Figs. 1 and 2 are shown accordingly a plurality of perfecting units of the so-called unit type press, arranged in two line series, one superimposed above the other, the preferable grouping being two unit-type perfecting printing units below, and two above, and at the end of this group of printing units, two pairs of side-by-side formers, the pairs being superimposed, with the necessary cross-folders. There are likewise four successive groups of these perfecting units and folding mechanisms as constituting a complete press. It will be quite obvious, however, that the size of the press could be increased indefinitely to meet the major requirements of any newspaper, and that the particular arrangement of printing units and folding mechanisms could likewise be widely varied, within the scope of our invention. The total capacity of a press of the size and arrangement shown will be more fully discussed hereinafter.

In accordance with certain features of the invention, one or more of the perfecting printing units in each group, say groups of four, as shown in Figs. 1 and 2 will be provided with mechanism for running the unit at either full-speed or half-speed and the usual web supplying mechanism will be used to supply a quarter-width, half-width, three-quarter width or full width web to this unit. The perfected half-speed web is severed into sheets and is associated with the full speed perfected webs in ways hereinafter described more fully, to provide the successive two-page increments that may be necessary or desirable for various runs or editions of the paper. 45

In the embodiment of Fig. 1, the printing units in the lower series are numbered from 1 to 8, and those in the upper series are numbered from 9 to 16, for purposes of description and identification in connection with the latter description of the various runs and arrangements for different sizes of products. The folders are likewise numbered for identification and similar purpose as F—1, F—2, F—3 and F—4. 55

The general press structure in Figs. 1 and 2 is shown only in sufficient detail as may be necessary or convenient in disclosing the present invention. The press comprises a longitudinally-disposed base frame 30, upon which the perfecting units of the lower series are mounted in the usual manner, this frame being provided with upright side frame members 31, upon which is supported the longitudinally-disposed side frame members 32, upon which are mounted the perfecting units of the uppermost series. A longitudinally-disposed top frame 34 is also provided, and the other parts and portions to the press frame need not be described in detail herein. 65

The folding mechanisms are indicated only generally, and as shown there is a pair of side-by-side formers 40 and 41 in line with the corresponding group of perfecting units in the top series, with a pair of former rollers 42 and 43 at the head of each former as usual. A similar pair

of formers 44 and 45 are similarly located with respect to the corresponding group of units in the lower horizontal series. In connection with each of the lower formers there is provided a sheet cutter and cross-folder 46, and the perfected and longitudinally folded webs may be run in any association desired from the formers to the cross-folders, as will be well understood.

Any suitable form of web supply may be provided, so far as concerns many features of the invention, it being borne in mind that the narrow-width webs for the slow-running printing unit or units may be supplied from the usual web-supplying mechanisms for the full-width webs. As embodied, there is provided beneath each perfecting printing unit of the lower series a web-supplying mechanism 50, adapted to provide a continuous web-supply without stopping the press, various forms of such devices being well-known and in common use. For the various perfecting units of the upper series, as embodied, similar sources 51 of web supply are located above the respective printing units, and preferably on the next-above floor of the building. In this particular arrangement, it is customary for the webs to be run upwardly from below into the respective printing units of the lower series and for the webs to be run down from above into the respective printing units of the upper series.

The perfected webs are preferably directed from the lower printing units upwardly, and from the upper printing units downwardly, into the space between the two superimposed series of printing units, and in said space the webs are guided, turned, slit and possibly cut into sheets, as may be found necessary or desirable in connection with running the various size and arrangements of products desired.

In the embodied form of driving mechanism, a general driving shaft 60 is journaled in bearings 62, carried on the side frame of the machine, there being clutches 63 provided for silencing any one of the branch drives for particular units or pairs of superimposed units, or other desired groups in the press. As embodied, in the branch drives, there is sleeved on the driving shaft 60 a bevel gear 65, and meshing therewith is a bevel gear 66, fixed on a vertically-disposed shaft 67, which shaft is journaled in bearings 68, mounted on the machine frame, and is provided with cooperating bearing collars 69. The vertical shafts 67 are used to drive two superimposed printing units, with an individual drive for each of the units.

The various perfecting printing mechanisms are preferably of the unit type, and as shown, each unit comprises a pair of form cylinders 115 and 120, and respective cooperating impression cylinders 105 and 110, all journaled in side frames 74 and 76 respectively, of the particular printing unit. The frames for the respective units are mounted on the general press frame. The respective inking mechanisms are shown fragmentarily and diagrammatically, and are indicated generally by the reference numerals 76, and may be of any suitable form.

The drive from shaft 67, for a perfecting unit or units in each group, or vertical series, which are driven at full speed (when not silenced) comprises a driving bevel gear 81, fixed on the shaft 67, and meshing with the bevel member 82 of a compound gear journaled on the machine frame, and comprising also an integral spur gear. The spur gear member 83 of this compound gear 75 meshes with a spur gear on one of the impression

cylinders, the three remaining cylinders of the two printing couples being driven therefrom by any known or suitable form of gearing, which need not be described in detail. It is possible to silence any of these perfecting units by suitable means, such as slipping the bevel gear 81 on its shaft 67, which may be done by removing the split collar 84, which may be of the usual form. Any vertical group of the perfecting units can be silenced by means of its clutch 63. It will be understood that these various features of construction may be widely changed or varied in so far as the main features of the present invention is concerned.

Referring now to the present preferred embodiment of means for driving any one or more of the perfecting units optionally at either full or half-speed, such mechanisms are shown applied to the two lowermost of the perfecting units of the group shown in Fig. 3. In most installations, however, it will be found sufficient to equip only one printing unit of such a group with the change speed mechanism.

Referring to said change speed driving mechanism in detail (Figs. 4 and 6) a bevel gear 91, 25 for full speed driving, is fixed to rotate with the shaft 67, and is slidable on the shaft by a spline 89 into and out of mesh with a bevel gear 92 of a compound gear 93, which latter is journaled loosely upon a stub shaft 94, mounted on the machine frame. In the drawings this gear is shown out of mesh, but is vertically movable into mesh, and may be held there by a split collar 95, interposable between the hub of the gear, and the journal lug or block 68. Also slidably mounted upon shaft 30 67 is a half-speed bevel gear 99, by means of a spline 100. This gear is movable into and out of mesh with a bevel gear 101 of a compound gear 102, which is journaled on a stub shaft 103, mounted on the machine frame. A similar split 35 collar 95 is employed to hold the bevel gear 99 in mesh with the bevel gear 101.

To drive the printing unit cylinders at either speed, both the spur gear 109 of compound gear 93, and the spur gear 110 of compound gear 102, 45 are continuously in mesh with a spur gear 104, fixed on the shaft 106 of an impression cylinder 105, the compound gear which is out of mesh with its driving bevel gear, as the case may be, rotating idly. Fixed on the opposite end of shaft 106 of impression cylinder 105, at the other side of press, is a spur gear 107, which meshes with a spur gear 116, fixed on shaft 117 of the plate cylinder 115. Impression cylinder 124 is driven by means of a spur gear 108, fixed on its shaft 109, and meshing with the spur gear 104, fixed on shaft 106 of impression cylinder 105. Similarly, plate cylinder 120 is driven by means of a spur gear 118, fixed on its shaft 119, and meshing with spur gear 121 on the shaft 109 of impression cylinder 124. 60 Thus by slipping either the driving bevel gear 91 or the driving bevel gear 99 into mesh with its corresponding compound gear, the perfecting printing unit may be run either at full speed or half-speed.

In the illustrated embodiment of means for handling, and for operating upon, the perfected webs from the various printing mechanisms, the webs from the printing units of the lower series are directed upwardly, and the perfected webs from the upper series are directed downwardly into the intervening space between the two series of units. In this space a slitting mechanism 122 is provided for each of the printing units, and beyond the slitters each unit is provided with a 75

pair of half-width, reversible angle bars 123. The slitters may be silenced, or may be driven at either full speed or half-speed as desired, and this may be done by any known or suitable mechanism, such as the usual or other suitable forms of slip gears and interchangeable speed change gears, which need not be illustrated. Means are likewise provided for directing the webs, when slit, either over the angle bars, or when not slit directly forward to the head rollers of the formers, both as shown in Fig. 3 of the drawings. It will be clear also that the webs may be associated in any desired relation, and may be run over as many or as few of the formers as need be, and the longitudinally folded products may be run to the folders in any desired arrangements. As shown in Fig. 3 all of the half webs are being directed to the lower pair of formers, some of the half webs going directly to the formers and some passing over the angle bars.

For the purpose of supplying the various desired sizes of product by optional two-page increments, there is further provided by our invention, in connection with the use of one or more half-speed perfecting units, one or more half-speed, sheet-cutting mechanisms 131, which may be of any known or other suitable form, and these may have cooperating sheet guiding and timing devices, which may likewise be of known or other suitable form. By means of said mechanisms the half-speed perfected webs, whether quarter-width, half-width, three-quarter width or full width, may be cut into sheets and directed to the formers as found convenient or desirable in connection with the particular size and association of the product.

In Fig. 7 a half-width slow web *a*, or a slit half of such a web is shown running through the half-speed sheet-cutter 131 and going over the former 44. In accordance with one feature of our invention the slow-speed sheet-cutter 131 is of half-width and is movable, or variably positionable longitudinally on its driving shaft 132, across the press.

In Fig. 8 the sheet-cutter 131 is shown positioned medianly with respect to the two formers 44 and 45. A supplementary slitter 137 is mounted on a driving shaft 138, and slits the perfected half-width web or sheet centrally, and one half thereof goes over each of the respective formers 44 or 45, thus simultaneously giving a two-page increment to the product passing over each of the formers.

A quarter-width web may be run through the half-speed perfecting unit to give an increment of two pages over the full capacity of webs from the full-speed units running to the same former. This quarter-width perfected web runs through the half-speed sheet-cutter, and the sheets are delivered into association with every other one of the corresponding pages in the perfected full-width and full-speed web or webs running to the same former. A half-width web may be run in like manner to give a similar increment of four sheets. A three-quarter width web may be run, with the slitter 122, and the slit quarter of the slow-speed web be run over the angle bars and associated with the half of the same web, this associated product being thereafter cut into sheets and fed into alternate association with the pages of the perfected web or webs running to the same former. Thus for every product it would be possible to run optionally six pages or four pages or two pages from the half-speed unit, into alternate association with one or more per-

fected webs coming from the full-speed printing units.

The perfecting units and the folding mechanisms may be variously grouped together to secure products of various maximum sizes, with the previously explained capacity of two-page increments and decrements, and also securing simultaneously a plurality of these products, of the desired or predetermined size, from the entire press. Assuming exemplarily a press of the size 10 and arrangement shown diagrammatically in Figs. 1 and 2, and having the mechanism and facilities shown more fully in the remaining figures, this press will produce from each group of four printing units any size of product, increasing by two pages, all the way up to fifty-four pages. For such products, printing units numbered 1, 2, 9 and 10 are run to folder No. 1; units numbered 3, 4, 11 and 12 are run to folder No. 2; units numbered 5, 6, 13 and 14 are run to folder 20 No. 3; units numbered 7, 8, 15 and 16 are run to folder No. 4; and units numbered 1, 3, 5 and 7 are run at half-speed. The quarter-width, half-width or three-quarter width webs for the half-speed perfecting unit, with the different associations, would be employed as already described.

Also by way of example, the sixteen printing units shown diagrammatically in Fig. 1 could be driven as three independent five-unit presses, and in this arrangement would furnish products going up by two-page increments to a maximum product of seventy pages. With this arrangement, units numbered 1, 2, 9, 10 and 11 would run to folder No. 1; units numbered 3, 4, 5, 12 and 13 would run to folder No. 2; and units numbered 7, 8, 14, 15 and 16 would run to folder No. 4. With this arrangement, printing unit number 6 and folder No. 3 would be silenced.

It will be understood from the foregoing that a press is provided having a very extensive range and flexibility in sizes of products through different arrangements and associations of printing units and folders and other mechanisms, and always with the facilities for two-page increments and decrements in product sizes; and it will be further understood that changes may be made in structures and arrangements exemplarily shown and described without departing from the principles of the invention and without sacrificing its chief advantages.

What we claim is:—

1. A printing press including in combination a plurality of perfecting press units arranged in line series each unit comprising a pair of printing couples, a slitter, a pair of formers at the end of said plurality of units, means for running one of said perfecting press units at full or half speed, and means located between a half-speed press unit and the formers for cutting off sheets from a half speed printed web and associating them with a full speed printed web prior to folding.

2. A printing press including in combination a plurality of perfecting press units arranged in line series each unit comprising a pair of printing couples, a slitter, a pair of formers at the end of said plurality of units, means for running one of said perfecting press units at half speed, means for guiding the printed webs from and above the press units to the formers, and means located above said printing units for cutting off sheets from a half speed printed web and associating them with a full speed printed web prior to folding.

3. A printing press including in combination a

- plurality of perfecting press units arranged in line series for perfecting a plurality of webs, a slitter, a pair of formers at the end of said plurality of units, means for running one of said units at full or half speed, means for severing the webs, and means for associating the pages of the half speed web with alternate pages of the full speed web.
4. A printing press including in combination a plurality of perfecting press units arranged in line series, a folding mechanism including a former at the end of said plurality of units, means for running one of said units at full or half speed, means for slitting the webs, means for cutting the half speed webs into sheets, and means for associating said sheets and a full speed printed web prior to folding.
5. A printing press including in combination a plurality of perfecting press units arranged in line series, a folding mechanism including a former at the end of said plurality of units, means for running one of said units at full or half speed, means for slitting the webs, means for cutting the half speed webs into sheets, and means for associating said sheets and a full speed printed web in alternate page relation prior to folding.
6. A printing press including in combination a plurality of perfecting printing units arranged in line series, at least one former in line with said series, means for supplying printed webs in various numbers to a former to produce different size products, including devices for optionally supplying a slow speed perfected narrow or full width web and means for cutting the longitudinally folded webs.
7. A printing press including in combination a plurality of perfecting printing units arranged in line series, at least one former in line with said series, means for supplying printed webs in various numbers to a former to produce different size products, including devices for supplying intermittently sheets from a slow speed perfected narrow or full width web.
8. A printing press including in combination a plurality of perfecting printing units arranged in line series, a slitter, a pair of formers in line with said series, and means for supplying printed webs in various numbers to the formers to produce different size products, including devices for supplying sheets in spaced apart relation from a perfected narrow width slow speed web.
9. A printing press including in combination means for perfecting a plurality of webs, means for slitting a web, and a half width cutting mechanism shiftable transversely of the web for cutting a slit web into sheets and means for associating said sheets with a perfected web in spaced apart page relation.
10. A printing press including in combination means for perfecting a plurality of webs, means for slitting a web, and a half width cutting mechanism for cutting a slit web into sheets, means for associating said sheets with a full width web, and means for subsequently folding and cutting the webs.
11. A printing press including in combination means for perfecting a plurality of webs, means for slitting a web, and a half width cutting mechanism for cutting a slit web into sheets and means for associating said sheets with a perfected web and means for subsequently folding and cutting the webs.
12. A printing press including in combination means for perfecting a plurality of webs, means for slitting a web, and a half width cutting mech-
- anism for cutting a slit web into sheets and means for associating said sheets with other of the perfected webs, a plurality of formers and devices for op-
- anism for cutting a slit web into sheets and means for associating said sheets with a perfected web in spaced apart page relation and means for subsequently folding and cutting the webs.
13. A printing press including in combination a plurality of web perfecting units arranged in line series, a plurality of web perfecting units arranged in line series in superposition upon said first series, a folding mechanism in line with said perfecting units, means for directing the webs between said two series of units to the folding mechanism, and sheet cutting means arranged between said series to deliver sheets to said folding mechanism.
14. A printing press including in combination a plurality of web perfecting units arranged in line series, a plurality of web perfecting units arranged in line series in superposition upon said first series, one at least of said web perfecting units being operable at half speed, a folding mechanism in line with said perfecting units, means for directing the webs between said two series of units to the folding mechanism, and sheet cutting means arranged between said series to deliver sheets from a half speed web to said folding mechanism.
15. A printing press including in combination a plurality of web perfecting units arranged in line series, a plurality of web perfecting units arranged in line series in superposition upon said first series, one at least of said web perfecting units being operable at half speed, a folding mechanism in line with said perfecting units, means for directing the webs between said two series of units to the folding mechanism, and sheet cutting means arranged between said series to deliver sheets from a half speed web to said folding mechanism.
16. A printing press including in combination means for perfecting a plurality of webs, means for slitting a web, and a fractional width cutting mechanism shiftable transversely of the web for cutting a slit web into sheets and means for associating said sheets with a perfected web in spaced apart page relation.
17. A printing press including in combination means for perfecting a plurality of webs, a fractional width cutting mechanism shiftable transversely of the web for cutting one of the webs into sheets.
18. A printing press including in combination a plurality of perfecting printing units arranged in line series, a plurality of formers, means for supplying perfected webs in various numbers to a former to produce different size products, including devices for optionally cutting and supplying a perfected narrow web, and selectively delivering it to one or another of said formers and means for cutting the longitudinally folded webs.
19. A printing press including in combination means for perfecting a plurality of webs, means for optionally running a web perfecting mechanism at different speeds, means for slitting a web, and a variably positionable partial width, half speed cutting mechanism for cutting a slit web into sheets.
20. A printing press including in combination a plurality of full-width perfecting printing units, means for supplying a fractional width web to one of said perfecting units, means for cutting said fractional width web into sheets, means for associating said sheets with other of the perfected webs, a plurality of formers and devices for op-

tionally directing the fractional width sheets to one or another of the formers.

21. A printing press including in combination means for perfecting a full width web, means operable at a slow speed for perfecting and cutting into sheets a fractional width web, side by side formers and means for associating said web and sheets and directing the fractional width web cut into sheets either to one side of two, or both sides of one, of the formers.

22. A printing press including in combination means for perfecting the full width web, means operable at a slow speed for perfecting and cutting into sheets a half-width web, side by side formers and means for associating said web with the sheets from said half-width web and directing said sheets either to one side of two, or both sides of one of the formers.

MARTIN W. BRUESHABER.
